MOTOR DRIVEN HAIR CUTTING IMPLEMENT

Barney R. Nyhagen, Bronx, N. Y.

Application July 14, 1936, Serial No. 90,555

5 Claims. (Cl. 30—43)

This invention relates to motor driven razors or hair cutting implements and broadly comprehends an improved device of this character wherein the movable cutter element is exposed for contact with the skin in order to serve as a means for raising the hair and properly guiding and presenting the same between the cutting edges of the teeth of the cutter elements, while the movable element also acts to massage the skin during the shaving operation.

More particularly the invention resides in a device of the indicated character which includes fixed and movable cutter elements each having teeth provided with cooperative cutting edges between which the hair to be cut is adapted to be engaged, the movable cutter element being so arranged as to contact with the skin in order to agitate and massage the same while functioning to raise the hair to a position perpendicular to the plane of the skin so as to properly guide and present the same to the cooperative cutting edges of the teeth and thereby insure a close and uniform severing of the hair without the necessity of employing shaving soaps or creams.

As a further feature, the invention provides in a device of the indicated character, a movable cutter element in which the toothed portion thereof is resiliently mounted and tensioned so as to pull and maintain the teeth thereof into frictional contact with the teeth of the fixed cutter element.

The invention is also directed to an improvement in the holder and actuator member for the cutter unit which resides in the provision of an eccentric or crank pin removably associated with the motor shaft terminal whereby said pin may be periodically replaced when worn to insure proper functioning of the device.

With the above enumerated and other objects in view, reference is now made to the following specification and the accompanying drawing in which there is disclosed, by way of example, a single embodiment of the invention, while the claims cover variations and modifications falling within the scope of the invention.

In the drawing:

Fig. 1 is a side view of a motor driven razor constructed in accordance with the invention and partially broken away to disclose the underlying structure.

Fig. 2 is a fragmentary enlarged sectional view therethrough taken approximately on the line 2—2 of Fig. 3.

Fig. 3 is a fragmentary enlarged plan view with parts broken away and shown in section.

Fig. 4 is an enlarged transverse sectional view taken approximately on the line 4—4 of Fig. 3.

Fig. 5 is an enlarged perspective view of the movable cutter element of the cutter unit.

Referring to the drawing by characters of reference, A designates generally the cutter unit and B the holder member therefor which member consists of a hollow handle constituting a housing for a motor 11 diagrammatically illustrated in the present instance as an electrical motor and having a shaft 12, one terminal of which extends into the groove 13 formed at one end of the handle. An element having an eccentric or crank pin 14 is carried by said shaft terminal and as illustrated, said element is removably associated therewith by threaded engagement with the same so that the said element may be periodically replaced when the crank pin is worn to insure proper functioning of the cutter unit.

The cutter unit A consists of a fixed cutter element 15 and a movable cutter element 16. The fixed cutter element 15 is of generally rectangular shape and the lower portion thereof is designed to snugly fit within the groove 13 of the end of the handle member B and is removably retained in place by means of a set screw 17 having a knurled manipulating head 18, the inner terminal of said screw engaging within a keeper depression 19 in one of the longitudinal side faces of the fixed cutter element.

The fixed cutter element is formed with a longitudinally extending circular bore 20 with which a longitudinal slot 21 communicates, which slot 21 opens through the upper surface of the fixed cutter element. The outer sides of the fixed cutter element 15 adjacent the slot are provided with longitudinally extending grooves or concavities 22 and the upper portion of the slot 21 is flared laterally outward to provide laterally and upwardly divergent surfaces 23. The upper portion of the fixed cutter element 15 is then provided with a surface of transverse parallel grooves defining teeth 24. A centrally arranged vertical opening 25 is formed in the lower portion of the fixed cutter element 15 and extends from the bore 20 downwardly through the lower surface of the fixed cutter element to receive therethrough the upper terminal of the shaft 12 and the eccentric pin 14.

The movable cutter element 16 consists of a substantially cylindrical base rod 26 of a diameter to snugly fit within the bore 20 of the fixed cutter element 15 and of a length approximately the length of said bore. The upper portion of said base rod 26 is provided with a flat longitudi-

50

55

nally extending face 27 and a cutter bar 28 is yieldably connected with the base rod 26 in superposed relation to the flattened upper surface 27.

5 As illustrated, the upper portion of the cutter bar 28 is formed with laterally projecting flanges 29, the undersurfaces of which are inclined laterally and upwardly to coincide with the laterally and upwardly divergent surfaces 23 of the 10 fixed cutter element while the upper surface is formed with transverse parallel grooves 30 corresponding to the grooves of the fixed cutter element and defining on the flanges 29 teeth 31 which cooperate with the teeth 24 of the fixed 15 cutter element to sever the hair when the movable cutter element 16 is reciprocated with reference to the fixed cutter element 15.

The base rod 26 of the movable cutter element is provided with a transverse notch 32 intermediate its ends and in the lower portion thereof to receive the eccentric or crank pin 14 whereby upon rotation of the motor shaft 12 reciprocation is imparted to the movable cutter element 16. The yieldable connection between the base 25 rod 26 and the cutter bar 28 consists of a pair of studs 33 threadedly engaged in the cutter bar 28 adjacent the opposite ends thereof and extending downwardly therefrom through apertures 34 into recesses 35 in the base rod 26 where 30 coiled expansion springs 36 surround the studs and are interposed between the kerfed heads thereof and the inner or upper ends 38 of the recesses 35 so that a tension is exerted to normally pull the lower surface of the cutter bar 28 into flat contact with the surface 27 of the base rod 26. Obviously, when the movable cutter element is positioned in the fixed cutter element 15, the tension thus exerted by the springs 36 will draw and maintain the inclined lower 40 surfaces of the flanges and the teeth 31 formed thereon into contact with the divergent upper surfaces of the teeth 24 to insure a proper contact thereof and a definite shearing action of the edges of the manipulating teeth 24 and 31.

45 In use and operation it will be apparent that the grooved upper surface of the movable cutter element 16 being exposed when shaving will contact with the skin in order to definitely agitate and massage the same to promote circulation coincident with the shaving operation. Likewise, the movement of the said movable cutter element while in contact with the skin will cause the moving teeth to raise the hair to a position perpendicular to the plane of the skin 55 and thereby properly guide and present the same to the co-acting cutting edges of the teeth thus insuring a close and uniform severing of the hair without employing shaving soaps and creams and without irritating the skin.

60 What is claimed is:

1. In a power driven hair cutting implement, a holder and actuating member and a cutter unit carried thereby including cooperative cutter elements relatively fixed and movable with 65 reference to said holder and actuating member, the fixed cutter element having a longitudinally extending bore and a longitudinally extending slot communicating with said bore and opening through the upper end of said fixed cutter ele-

ment with laterally and upwardly divergent upper surfaces on opposite sides of said slot, the upper end of said fixed element having longitudinally spaced transverse grooves, the movable cutter element comprising a base slidably fitted within the bore and a cutter bar fitted within said slot and provided with lateral flanges having upwardly inclined under surfaces and formed with longitudinally spaced transverse grooves, and resilient means for drawing said under surfaces of the flanges into contact with the upper surfaces of the fixed cutter element. 5 10 15

2. A shaving device comprising a toothed stationary cutter member having a recess therein, and a toothed movable cutter member reciprocably mounted in said recess and having substantially its teeth only overlying the teeth of said stationary cutter member, the underside of the teeth of said movable member engaging against the outer surface of the teeth of said stationary member and the outer surface of the teeth of said movable cutter being adapted to directly engage the skin, the teeth of said stationary cutter member being integral therewith and the outer surface of said movable member 25 being wholly free of overlying portions of said shaving device whereby all of said outer surface is directly engageable with the skin. 20 25

3. A shaving device comprising a fixed member having a plurality of integral spaced teeth 30 and a recess adjacent thereto, the spaces between said teeth being open at one end to permit hair to enter between said teeth, and a movable cutter member in said recess having a plurality of thin spaced teeth reciprocable over and in 35 engagement with the outside surfaces of said first named teeth, said movable cutter member having substantially its teeth only overlying the teeth of said fixed member, the spaces between said last named teeth being open at one end to 40 permit hair in said first spaces to enter between the second named teeth to be cut as said cutter member moves, and the outer surface of said movable member being wholly free of overlying portions of such shaving device whereby all of 45 said outer surface is directly engageable with the skin.

4. A shaving device comprising a fixed block provided with a channel groove extending longitudinally therein, the upper surface of said block 50 on each side of said groove being formed with spaced teeth, a reciprocable cutter block in said channel groove having a thin toothed portion overlying and engaging the upper toothed surfaces of said fixed block, and means for reciprocating said cutter block. 55

5. A shaving device comprising a fixed block provided with a channel groove extending longitudinally therein, the upper surface of said block on each side of said groove being formed with 60 spaced teeth, a reciprocable cutter block in said channel groove having a thin toothed portion overlying and engaging the upper toothed surfaces of said fixed block, and means for reciprocating said cutter block, the teeth of said cutter block lying wholly within the edges of said fixed block. 65
